UNITED STATES PATENT OFFICE.

WILLIAM S. HARLEY, OF MILWAUKEE, WISCONSIN, ASSIGNOR TO HARLEY-DAVIDSON MOTOR CO., OF MILWAUKEE, WISCONSIN.

ENGINE-STARTER.

1,137,314.

Specification of Letters Patent. Patented Apr. 27, 1915.

Application filed July 7, 1913. Serial No. 777,704.

To all whom it may concern:

Be it known that I, WILLIAM S. HARLEY, a citizen of the United States, and resident of Milwaukee, in the county of Milwaukee, 5 and State of Wisconsin, have invented certain new and useful Improvements in Engine-Starters; and I do hereby declare that the following is a full, clear, and exact description thereof.

10 My invention has for its object to provide a simple, economical and effective starter for internal combustion engines, the same being particularly designed to economize in the application of power for effecting a 15 starting movement.

The construction and arrangement of my invention is such that a valve-controlled vent of the engine cylinder is first opened, whereby compression is eliminated and thereafter 20 the engine-shaft is given a predetermined number of initial revolutions prior to an automatic closing movement of the valve to effect a starting operation. Thus momentum is obtained in the initial free rotation of 25 the engine-shaft and thereafter the valve mechanism is tripped whereby a compressed charge is fired.

With the above objects in view the invention 30 consists in various structural features and combination of mechanical elements to be hereinafter set forth with reference to the accompanying drawings and subsequently claimed.

In the drawings Figure 1 represents a dia- 35 grammatic partly sectional elevation of a starting mechanism embodying the features of my invention shown in connection with an engine; Fig. 2, a detailed cross-section of an engine-shaft clutch mechanism utilized 40 as one element in carrying out my invention, and Figs. 3 and 4, detailed sectional views of the same, the sections being indicated by lines 3—3 and 4—4 respectively of Fig. 2.

Referring by characters to the drawings, 45 1 represents a cylinder of a standard type of internal combustion engine, 2 the piston, and 3 the engine crank-shaft which is connected to said piston in the usual manner. The cylinder is provided with an intake 50 valve 4 and an exhaust valve 4' which controls the vent aperture, the said valve being held to its seat by a spring 5 which is interposed between a sleeve extending from the cylinder and a collar 5' that is secured to the valve-stem. One arm of a bell-crank

lever 6 is adapted to engage the collar and lift the valve, whereby the vent aperture is opened, the said bell-crank lever being fulcrumed to the engine casing. This bell-crank lever is connected to a second bell-crank lever 7 by a rod 8 or other connection, as shown, the second bell-crank lever being fulcrumed to a bracket that is suitably secured to the dashboard 9 or other fixed portion of a vehicle body accessible to the operator. One arm of the bell-crank lever 7 is provided with a handle whereby said lever may be manually shifted, said arm being extended through a slot in the dashboard. The short arm 7' of the hand-controlled bell-crank lever is forked at its end and arranged to straddle a cord 10 or other connection, which cord passes over a guide-sheave 11 and is wound about a clutch-drum 12, the end of the cord being secured thereto. The 60 opposite end of this cord or connection extends through an aperture in the dashboard 9 and terminates with a hand-grip 10', whereby the said cord may be manipulated by the operator. This cord carries an adjustable tappet 13, the tappet, in this instance, comprising a collar that is secured to the cord by means of a set-screw and also comprises a coiled buffer spring which is interposed between the collar and a washer 13' that is slidable upon the cord. By this connection the washer 13' of the tappet is 65 adapted to engage the short arm 7' of the lever 7, whereby the latter is actuated in one direction and the buffer spring permits yield to prevent sudden shock incidental to pulling of the cord by the operator. The clutch-pulley 12 is loosely mounted upon the engine-shaft 3 and forms no part of my invention, its construction being clearly shown and described in an application filed by me 70 March 11, 1913, Serial No. 753488, for improvements in transmission gearing. The clutch-pulley carries a series of dogs 14 that are adapted to engage a ratchet-wheel 15, which ratchet-wheel is secured to the engine-shaft, the dogs being provided with tails that engage the side faces of the ratchet-wheel, whereby they are thrown out of engagement with the same co-incident to power being applied to the shaft through the engine. The clutch-drum also has secured thereto one end of a coiled spring 16, while the opposite end of said spring is fast to a 75 cross-beam 17 that constitutes part of the 80

superstructure of a device or vehicle to which the engine is applied.

From the foregoing description it is apparent that when it is desired to start the engine from the seat of the vehicle the operator first manipulates the bell-crank lever 7, whereby it assumes the position shown in Fig. 1 of the drawings. Thereafter the cord 10 or other connecting element to the drum is drawn forward in the direction indicated by the arrow and this movement imparts rotation to the clutch-drum 12, which, in turn, causes the engine-shaft to rotate a predetermined number of revolutions in the direction indicated by the arrows in Figs. 1 and 3. The tappet 13 will thus engage the short arm of the lever 7, while there is approximately one winding of said cord upon the clutch-drum, and hence at this moment of engagement the vent valve will be tripped by the bell-crank lever mechanism and the final rotation imparted to the engine crank-shaft will be sufficient to explode a charge of gas introduced into the firing head of the engine, the exhaust valve of which at this time is shut. It is understood the final rotation imparted to the engine shaft through the cable causes the tappet 13 to travel past the short arm 7' of the lever, and upon the return of the cable, due to the clutch drum winding spring, there is sufficient slack in said cable to permit the tappet to pass under the aforesaid lever arm without tripping the same from its now locked position. Hence it will be seen that, owing to the

timed relation between the means for controlling the exhaust valve and the means for rotating the engine shaft, that great economy in the power necessary to start the engine will result and that said starting moment can be absolutely determined by previous set of the related mechanism.

I claim:

In an internal combustion engine having a cylinder, a piston therefor, a crank shaft connected to the piston, a clutch drum carried by the crank shaft, a vent for the cylinder, and a valve for said vent; the combination of a starting mechanism comprising manually operated actuating means for the vent valve, locking means for the vent valve actuating means, whereby said valve is held open, a manually operated actuating means connected to the clutch drum, whereby the latter is rotated in one direction, and a tappet carried by the clutch drum actuating means engageable with the vent valve locking means, whereby said valve locking means is released to effect closure of the vent valve after the clutch drum has been rotated a predetermined extent.

In testimony that I claim the foregoing I have hereunto set my hand at Milwaukee in the county of Milwaukee and State of Wisconsin in the presence of two witnesses.

WILLIAM S. HARLEY.
